A. W. CURTIS,
ONE-MAN TOP FOR AUTOMOBILES.
APPLICATION FILED FEB. 21, 1916.

1,293,355.

Patented Feb. 4, 1919.

UNITED STATES PATENT OFFICE.

ALMON W. CURTIS, OF CORTLAND, NEW YORK.

ONE-MAN TOP FOR AUTOMOBILES.

1,293,355.

Specification of Letters Patent.

Patented Feb. 4, 1919.

Application filed February 21, 1916. Serial No. 79,649.

To all whom it may concern:

Be it known that I, ALMON W. CURTIS, a citizen of the United States of America, and resident of Cortland, in the county of Cortland, in the State of New York, have invented new and useful Improvements in One-Man Tops for Automobiles, of which the following, taken in connection with the accompanying drawings, is a full, clear, and 10 exact description.

This invention relates to certain improvements in one-man tops for automobiles, and refers more particularly to the structure of the bows proper, as distinguished from the 15 "sockets," and to the means for attaching the ends of the bows to said sockets or to their supporting braces.

The bows now in common use are made of wood, and aside from the fact that it is 20 necessary to make them of relatively large cross sectional area in order to give the desired strength, they must be made of selected quality to permit them to be milled and bent to the required form and size, and it 25 frequently happens that the imperfections will not develop until after the bows have been practically finished so that a considerable percentage of the total output are unfit for use and must be thrown aside as waste. 30 at a considerable loss to the manufacturer.

Furthermore, the ends of the wooden bows must be finished or milled with great accuracy in order to fit closely in the tapering sockets into which they are tightly driven 35 with the further requirement that considerable care must be taken to properly adjust the bows in the sockets to support the top symmetrically, and at the desired height, all of which entails considerable trouble and expense.

It is also customary to cover these wooden bows with fabric sheaths which are usually made up in the form of tubes of the required size and then drawn over and upon the bows, 45 and in many instances owing to the lack of uniformity in the size of the bows and fabric tubes, the latter are frequently ripped or torn in the operation of drawing them on the bows, the mutilated sheaths being usually thrown away, resulting in additional 50 loss to the manufacturer, the sheath being usually of such color as to conform to the linings of the top.

These losses are considerably increased by the fact that it is extremely difficult to obtain the desired quality of wood, and one of the main objects of my present invention is to obviate such difficulties and losses by providing tubular metal bows with relatively shallow lengthwise channels opening 60 through the upper faces thereof for receiving relatively narrow strips of wood or equivalent material capable of receiving tacks or similar fastening devices by which the lining of the top is secured to the bows. 65

Another object is to obviate the necessity for the sockets which support the front portion of the top by providing less bulky substitute supports therefor and to construct such substitute supports in such manner as 70 to enable the top to be clasped or dropped into a more compact space than has heretofore been practicable.

Other objects and uses relating to specific parts of the device will be brought out in the 75 following description.

In the drawings—

Figure 1 is a longitudinal sectional view of a one-man top embodying the various features of my invention, shown by full lines 80 as extended for use, and by dotted lines as clasped or dropped.

Fig. 2 is an enlarged transverse sectional view taken on line 2—2, Fig. 1.

Fig. 3 is a longitudinal sectional view 85 through the adjacent ends of the bow and socket taken in the plane of line 3—3, Fig. 2, and showing more particularly the coupling between the bow and socket.

Fig. 4 is a perspective view, partly broken 90 away, of one of the detached couplings.

Fig. 5 is an enlarged longitudinal sectional view through the adjacent ends of the front bow and one of its supporting braces, taken on line 5—5, Fig. 1. 95

Fig. 6 is a sectional view similar to Fig. 2 of a modified form of bow, showing in end elevation the coupling for attaching the same to the socket.

Fig. 7 is a transverse sectional view of the 100 bow section showing the manner of fastening the top thereto.

As illustrated, the top comprises a flexible covering —A— and a plurality of, in this instance four, supports therefor comprising 105 a main center support —1—, a rear support

—2—, a front support —3— and an intermediate support —4—, all of which are provided with arched or U-shaped bow sections —5— of similar construction, hereinafter described, and arranged to support the fabric covering —A— at suitable intervals throughout its length and to impart the desired shape thereto when adjusted for use.

The ends of the bows —5— of the main support —1— and rear support —2— are connected by couplings —6— to suitable brace sockets —7— and —8—, while the ends of the front and intermediate bows —5— of the supports —3— and —4— are telescopically connected with suitable braces —9— and —10—, which, in turn, are pivotally connected in a manner presently described to corresponding brace bars —11—, the latter being pivoted at —12— to the main socket braces —7— at points slightly above the lower edges of the side quarters, as —a— of the cover —A— so that the braces —9—, —10— and —11— will be concealed from external view when the top is adjusted for use.

The main socket braces —7— are pivoted at —13— to suitable supports on the side of the top just back of the entrance to the rear seat, while the socket braces —8— are pivoted at —14— to rearwardly projecting lugs on the lower ends of the socket braces —7— so that the sockets —7— and —8— at the same side of the top will lie in substantially the same longitudinal vertical plane, the lengths of the main support —1— and rear support —2—, of which the sockets —7— and —8— form a part, being sufficient to allow the top —A— to clash or fold beyond the rear end of the body, as —B— indicated by dotted lines.

The rear ends of the brace bars —11— are preferably pivoted to the inner side of the main socket braces —7— and are of slightly less length than the distance between the pivots —12— and —13— so as to permit them to fold or clash inside of the main sockets —7— when the top is lowered to the position shown by dotted lines.

The brace bars —9— and —11— at the same side of the top are pivoted to each other at —15—, thus forming a toggle joint, the pivots —15— for both sets of braces being disposed above the horizontal plane of a direct line drawn between the pivots —12— and points of attachment of the front end of the covering —A— with the corresponding edge of the front support —3— when the top is adjusted for use so as to produce toggle locks for holding the top in its extended position, the adjacent ends of the connected bars —9— and —11— being provided with stop shoulders —16— to limit the upward movement of the toggle joint.

The brace bars —10— are pivoted at —17— to their respective bars —11— inter-

mediate the ends thereof so as to cause the corresponding support —4— to properly clash with the other supports when the top is let down.

The manner of connecting the brace bars depends somewhat upon the number of cover supports used, and inasmuch as such number varies in accordance with the length of the top, the exact manner of connection is immaterial so long as they permit the cover supports to be properly clashed and extended.

The particular features of the invention, therefore, reside in the peculiar structure of each of the bow sockets —5— and their connections with the sockets —7— and —8— or brace bars —9— and —10—, and also the manner of connecting the bars —11— to the socket braces —7— so that the bars —11— will clash inside of the main brace bars, thereby permitting the entire top to clash within a more compact space than would be the case if the front and intermediate bows —5— were secured to sockets, as —7— and —8—.

Each bow section —5— comprises a tubular sheet metal bar —18— formed from a single strip of sheet metal and arched or U-shaped longitudinally and having its outer side depressed inwardly to form a lengthwise channel —19— for receiving and retaining a relatively narrow strip —20— of wood or other comparatively inexpensive material capable of receiving tacks or nails by which the cover or the lining thereof may be secured thereto, the opposite longitudinal edges of the strip being engaged along the inner wall of the channel to complete the tubular formation of the metal section of the bow.

In the preferred form of bow section shown in Figs. 1, 2, and 3, the outer edge of the metal tube —18— is compressed or reduced in width while the central depressed portion of the outer portion thereof forming the channel —19— is of considerably less depth than the total corresponding depth of the entire bar or bow, thus forming a lengthwise chamber —21— to decrease the weight of the bow without sacrificing its strength, the depressed portion, as —22—, at the inner side of the channel, serving as a seat for the wooden strip and also to clench or deflect the points of the tacks or nails used in fastening the covering to the wooden strip, as shown in Fig. 7.

After the wooden strip or strips —20— are inserted in the channel —19—, the opposite sides of the tube are tightly compressed against the adjacent sides of the wood to retain the same in operative position so that in the completed bow the channel and wooden strip are dove-tailed or inverted key-stone shaped in cross section, but if necessary these strips may be re-

tained by pins —23— passing therethrough and through opposite sides of the tube, as shown in Fig. 2.

The couplings —6— for clamping the 5 ends of the bow —5— to their corresponding sockets, as —7— and —8—, are each provided with a lengthwise tapered portion —24— of substantially the same cross 10 sectional form and size as the interior of the larger open end of the socket so as to fit tightly therein with a wedge fit, leaving a relatively shorter portion of the coupling 15 protruding beyond the open end of the socket for receiving the adjacent end of the tubular section of the bow —5—, the outer 20 end of said coupling being provided with a shoulder —25— adapted to abut against the corresponding end of the socket for limiting the telescoping movement of the socket and coupling relatively to each other.

The protruding end of the coupling is gradually reduced in cross sectional size toward its free end and is provided with a 25 lengthwise opening —26— of substantially the same cross sectional form and size as the tube —18—.

The coupling is preferably hollow from 30 end to end and is divided longitudinally through diametrically opposite sides to form opposite clamping sections, the meeting edges at one side being provided, respectively, with a V-shape groove —27— and a V-shape rib —28— substantially 35 midway between the ends for interlocking engagement with each other to prevent relative endwise movement of the sections when the coupling is being inserted into the socket, by which action the coupling 40 sections are tightly drawn against the interposed portion of the bow tube —18—, thus frictionally locking the coupling to the socket and also to the bow.

In some instances, however, it may be 45 necessary to use extra fastening means, such as brazing or soldering, for securing the coupling to the bow and also to the socket, which may be done without departing from the spirit of my invention, the purpose being 50 to couple the ends of the tubular bow to the sockets in as simple a manner as possible, and at the same time to produce a neat and trim connection without cumbersome or unsightly projections.

55 The frictional grip of the head of each coupling upon the tubular bow is materially increased by extending the solid portion of the head a short distance into the open end of the socket, while the walls of 60 the remaining portion of the socket are comparatively thin and, therefore, more yielding than the solid portions of the head, so that when the open end of the socket encounters the solid portions of the head 65 during the insertion of the coupling into

the socket, it will tend to force said solid portion more tightly against the tube —18—, it being understood that sufficient clearance is left between the meeting edges of the coupling sections to allow them to 70 impinge tightly against the adjacent ends of the tubular bow.

The brace bars —9—, —10— and —11— are preferably solid and somewhat flat or slightly elongated in cross section and are 75 arranged edgewise vertically, thus permitting them to be made of very much smaller size than the sockets usually employed for receiving the bow sections —5—, whereby the entire top may be clashed or folded into 80 a more compact space than would be the case if the ordinary sockets were used for supporting the front and intermediate bows.

In the use of these bow-supporting braces 85 —9— and —10—, the latter are provided with extensions —29— of substantially the same cross sectional size and form as the chamber —21— in the tubular bow —18— and are inserted into said chambers and secured 90 therein by rivets —30—, the portion of each brace at the base of the extension —29— being provided with stop shoulders —31— for limiting the telescopic movement of the tubular bow and brace relatively to each other.

This manner of assembling either of the bows —5— upon their respective braces —9— or —10— leaves the ends of the wooden strips —20— wholly at one side of 100 the extension —29— with the portion —22— of the tube at the base of the channel and inner side of the tube in close contact with the corresponding sides of the extension —29— for firmly locking the braces and 105 ends of the bow against relative lateral movement.

The metal tube shown in Fig. 6 is somewhat similar to that shown in Fig. 2, except that its outer edges at opposite sides 110 of the channel in which the wooden strip —20— is placed are not pressed inwardly.

The front bow —5— may be supported upon the wind shield or other suitable support by any well known means not necessary 115 to herein illustrate or describe for the reason that such fastening means forms no part of my present invention.

By making the bows of separate strips of sheet metal, the bearing faces for receiving and supporting the cover may be readily bent to any angle relatively to the direction of extension of the supporting braces, thus always affording a flat bearing surface with the wooden filler adjacent such covering 125 for receiving the tacks by which the cover is secured to the bow, such a condition being practically impossible in the use of wooden bows which require considerable labor in beveling or chamfering the edges to form a 130

sufficient bearing for the top, particularly in the front, intermediate and rear bows or in any other bow which is not capable of being disposed at substantially right angles 5 to the plane of the covering.

Furthermore, by making the metal bows 10 separate from their supporting braces, it is possible to manufacture such bows in standard sizes more conveniently than would be possible if the bows and their supporting 15 braces were all made in one piece which would be practically prohibitive in most of factories by reason of the large space which would be required for forming, while on the 20 other hand, this bow with the coupling may be used in connection with any of the standard forms of sockets.

In practice, the length of the bows is 25 slightly less than the transverse width of the covering including the side quarters so that the joints between the bows and their supporting braces are concealed from external view when the top is adjusted for use.

The web —22— of the tubular bow not 30 only serves to clench the tacks or nails into the filler —20—, but also serves to reinforce or stiffen the bow against buckling.

Another important advantage of the tubular metal bows is that they may be made 35 of uniform size and shape without liability of warping or otherwise deforming, thereby avoiding excessive waste of time and labor in refitting so common in the use of wooden bows, and, furthermore, these bows may be 40 painted, enameled or japanned in color to harmonize with the color of the top or lining, thus obviating the necessity for sheaths or coverings of fabric also commonly used for wooden bows.

40 What I claim is:

1. In a folding vehicle top, a cover-supporting bow consisting of a sheet metal tube having a channel in its outer face and a transverse wall forming the base of the

channel and spaced apart from the inner 45 wall of the tube, and a wooden filler seated in said channel.

2. In a folding vehicle top, a cover-supporting bow consisting of a sheet metal tube having a channel in its outer face and a 50 transverse wall forming the base of the channel and spaced apart from the inner wall of the tube and a wooden filler seated in said channel, the outer edges of the side walls of said channel being slightly contracted to retain the wooden filler therein. 55

3. In a folding top for vehicles, the combination of a pair of tubular braces, a separate tubular sheet metal bow section spanning the distance between the braces and 60 provided with a lengthwise channel in its outer face extending from end to end thereof and forming a wall at the base of the channel spaced from the inner wall of the tube, a wood filler fitted within and extending from end to end of said channel, and couplings connecting the ends of the bow to corresponding ends of the braces.

4. In a folding top for vehicles, the combination of a pair of socketed braces, a 70 separate sheet metal bow section having its ends registered with the sockets in the braces, said bow section being provided with a lengthwise channel in its outer face extending from end to end thereof, longitudinally split couplings having tapered ends 75 fitted in said sockets and their outer ends embracing the adjacent ends of the bow section, and a wood filler fitted within the channel of the bow section and extending from 80 end to end thereof.

In witness whereof I have hereunto set my hand this 19th day of February, 1916.

ALMON W. CURTIS.
